UNITED STATES PATENT OFFICE.

DELBERT S. DAVIDSON, OF Veedersburg, Indiana.

PLATE-LIFTING DEVICE.

1,232,234.

Specification of Letters Patent.

Patented July 3, 1917.

Application filed June 23, 1916. Serial No. 105,450.

To all whom it may concern:

Be it known that I, DELBERT S. DAVIDSON, a citizen of the United States, residing at Veedersburg, in the county of Fountain and State of Indiana, have invented new and useful Improvements in Plate-Lifting Devices, of which the following is a specification.

The present invention has for its object to provide a simple and practical device for lifting and removing the usual culinary vessels, such as pie plates, pans and other dishes used in cooking and the said invention resides in the novel construction, combination and operative arrangement of parts set forth in the following description and falling within the scope of the appended claim.

Figure 1 is a perspective view of the device illustrating the same in the act of lifting a plate, the plate being illustrated in dotted lines;

Fig. 2 is a side elevation showing the jaws in closed position; and

Fig. 3 is an enlarged view clearly illustrating the manner of connection of the movable jaw with the device.

Referring more particularly to the accompanying drawing, in which like characters of reference refer to corresponding parts in the several views, the lifting device for culinary vessels is designated generally by the reference character 5, and is illustrated as constructed from wire. In constructing the device, I employ a single strand of wire 6 intertwined for the greater portion of its length to provide a handle 7 and thence coiled at the rear end of the handle to provide an eye 8 permitting of the device being suspended from a support, not shown, when the use of the same is found undesirable.

The forward end of the intertwined portion of wire forming the handle 7 is extended in a longitudinal line with the handle 45 to form a crank arm 9 bent at spaced intervals to provide offset U-shaped bearings 10, the purpose of which will be hereinafter more fully set forth as the description of the invention is proceeded with. The opposite 50 terminal of the strands of wire 6 constituting the intertwined portion forming the handle 7 is offset laterally to provide a substantially U-shaped fixed jaw 11, by bending the strand laterally as indicated by the reference character 12 forming one of the limbs 55 of the jaw, thence continued and bent form-

ing a substantially oval-shaped connecting portion 13, the terminal of such connecting portion being thence extended in a direction toward the shank and in parallelism with the limb 12 thereof, forming the opposite limb 14, forming the jaw of a configuration of the above stated character. The limb 14 of the rigid jaw is coiled around the outer end 15 of the crank arm for connecting the free end of the jaw with the said crank arm.

16 designates a movable jaw which likewise is of substantially U-form constructed from a single strand of wire bent to provide the same with a pair of spaced limbs 17 connected to one another through the medium of the substantially oval-shaped connecting portion 18. The terminals of the limbs 17 of the movable jaw are bent to form trunnions 19 engaged in the offset bearings 10 and connecting the movable jaw with said crank arm 9 for horizontal swinging movement.

In briefly describing the operation of this invention, it is to be stated when it is desired to lift a culinary vessel, such as a pie plate, dish, pan or the like, the jaw 16 is swung to an open position and engaged under the flange 20 of the vessel to be lifted. The operator then turns the handle 7 of the device in a direction away from the movable jaw 16, thus automatically moving the rigid jaw 11 into clamping engagement with the opposite diametric point of the clamping flange 20 of the vessel to be lifted, thus it will be seen by this operation a firm gripping action of the jaws with the vessel is obtained.

From the foregoing description, taken in connection with the accompanying drawing, the advantages of construction and of the method of operation will be readily apparent to those skilled in the art to which the invention relates, and while I have described the principles of operation of the invention, together with the device which I now consider to be the best embodiment thereof, I desire to have it understood that the device shown is merely illustrative, and that such changes may be made when desired as are within the scope of the claim appended thereto.

I claim:

A device for lifting pie plates, pans, dishes, and the like articles embodying a handle formed at its forward end with a crank arm having U-shaped bearings, a fixed

- jaw formed integral with the handle and extended laterally therefrom, the free end of said jaw being connected with the terminal portion of the crank arm, a movable jaw 5 pivotally supported in the U-shaped bearings of the crank arm for horizontal swinging movement, said fixed jaw upon the en-

gagement of the movable jaw with the article is automatically brought into clamping engagement with the article upon imparting 10 a turning movement to the handle.

In testimony whereof I affix my signature.

DELBERT S. DAVIDSON.
